(57) **CLAIM**

The ornamental design for a loose leaf binder, as shown and described.

DESCRIPTION

FIG. 1 is a front view of the loose leaf binder according to the invention;

FIG. 2 is a rear view of the loose leaf binder according to the invention;

FIG. 3 is a left side view of the loose leaf binder according to the invention;

FIG. 4 is a right side view of the loose leaf binder according to the invention;

FIG. 5 is a top view of the loose leaf binder according to the invention;

FIG. 6 is a bottom view of the loose leaf binder according to the invention;

FIG. 7 is an enlarged cross sectional view taken along the lines 7—7 of FIG. 1;

FIG. 8 is an enlarged cross sectional view taken along the lines 8—8 of FIG. 1;

FIG. 9 is a perspective view of the loose leaf binder according to the invention; and,

FIG. 10 is an enlarged view taken along the lines 10—10 of FIG. 5.
